BALANCING MACHINE

James John Guest, Bromley Common, England

Application December 16, 1943, Serial No. 514,553
In Great Britain September 25, 1942

2 Claims. (Cl. 73—66)

This invention relates to means for supporting and controlling the motion of a frame upon which, in particular, rotors are mounted in order that they may be tested for the corrections necessary to render them in balance. The frame is firstly carried on the supporting part or base so that its only possible motions are those in which every point of it moves parallel to a certain plane or sufficiently closely thereto, herein termed planar motion. An object of the invention is to provide in a testing machine of the above character a plurality of taut flexible members fixed to the stationary base and extending a spaced distance from and substantially parallel to the plane of the frame, one of the flexible members disposed longitudinally and another transversely of the frame, with means for connecting the frame to either of the flexible members to restrain planar movement of the frame parallel to the flexible member to which it is connected.

This planar motion of the frame may be effected in any known manner; the preferred manner, however, is to connect the frame to the supporting base by three or more parallel and sufficiently flexible members. These members may be in tension, when merely hinged rods or cords in the manner of tri-filar suspension would serve, or in compression and acting by their flexibility, the control for small movements such as are to be used then giving a sufficiently close planar movement to the frame. In the preferred apparatus the supporting members, either tension or compression, act by their flexibility and give an elastic determination of the position of equilibrium, which may be further determined by other spring fittings added to control the natural period of vibration of the frame. These supporting members, which may be of any section, are preferably firmly connected at their ends to the frame and to the base so that the frame moves under the flexibility of the supports only, and even such friction as occurs in rolling is eliminated. The supports are such that their axial strains produce insignificant effects.

These supporting members may be arranged in any manner. In a convenient construction the frame may be regarded as having a flat horizontal upper surface intended to carry the rotor with its axis horizontal and parallel to the length of the frame, which frame may be of a rectangular shape and supported at each corner, with intermediate supports if desirable. In the following description it will be convenient to regard the construction as being thus, but actually any relatively equivalent arrangement may be used.

The invention will be better understood from the following detailed description considered in connection with the accompanying drawing, in which

Figure 1 is a view in side elevation of a balancing machine embodying the invention;

Figure 2 is an end view of the machine of Fig. 1; and

Figure 3 is a plan view with the structure supported by the frame omitted for the sake of greater clearness.

The arrangement is shown in Figures 1, 2 and 3, in which the frame 1 is shown supported on the base 2 by four elastic supports, 3, 4, 5 and 6, one at each corner, acting in compression. The support members are of equal length for convenience and connect points in one plane in the frame to points in one plane in the base, both these planes being horizontal. For small movements, then, the frame moves with planar motion within insignificant amounts. The rotor R to be tested is supported in bearings 7 and 8 carried on the frame, with its axis A—A horizontal and parallel to the side of the frame. In the operation of testing, the rotor revolves but as this does not cause any appreciable tendency to displacement of the frame in the direction of the axis A—A, restraint against motion in this direction is not actually necessary. Nevertheless, it is desirable that the frame should be so restrained. This restraint here is termed the axial control, and when effected it leaves the frame with two degrees of freedom, one of which is removed by a further restraint, termed the final control.

These controls consist in limiting the motion of a selected point of the frame to one line, which of course will be horizontal as regards this description. The limitation may be effected in any known manner. Preferably the construction is as follows: A flexible wire 9 is held at its two ends at points 10 and 11 in the base or in brackets thereon, and at an intermediate point 12 is attached to the frame, or to a bracket thereon so that, the wire 9 being tight, the point at which it is attached to the frame is prevented from moving in the direction of the wire, except for exceedingly small movements, but is capable of small but much larger movements perpendicular to this line by virtue of the elasticity of the wire. In the restraint above referred to, the wire 9 is set parallel to the axis of the rotor and, as limiting movement of the frame in the axial direction, is thus the axial control. As mentioned above, it is not absolutely necessary and so may sometimes be omitted for reasons of cheapness or simplicity.

As there is no great tendency to motion axially, sufficient restraint against such movement can sometimes be given by making the supports of a section having greater resistance to bending in the direction A—A than in a perpendicular direction, and in this case, if the supports are of suitable stiffness, the primary control previously described may be omitted.

The frame having thus an axial control of either type, it is subjected to a further restraint, again confining the motion of a point on the frame to a (here horizontal) line and again by any known means but preferably by the means above described. Such a final control is shown in the figures where a flexible strip 13 is fastened to the base at the points 14 and 15 and to the frame at the point 16. This control is shown as arranged in a machine for dynamic balancing and is set with the strip perpendicular to the axis of the rotor so that the movement of the point 16 in a direction perpendicular to the axis of the rotor is prevented. It is thus termed a cross-control. The only appreciable motion of the frame remaining is that of rotation about a line perpendicular to the planar motion of the frame (a vertical line as described), passing through the intersection of the flexible elements in the plan view; that is, through the point in which elements 9 and 13 coincide as shown in Figure 3.

For dynamic balancing it is frequently convenient that the frame can have alternative rotation about some other axis parallel to this axis, and to this end a second such final control 17 is arranged perpendicular to the rotation axis. This cross-control may be fitted so that the position of the point fixed along the axis may be adjusted or so that it is fixed in position. In the figures, one control—that of point 16—is shown as fixed and another is shown as adjustable. The second cross-control comprises a strip 17 fastened to the base at 18 and 19 and to the frame at 20. As only one of the final cross-controls 13 and 17 is in use at one time, they are arranged to be easily released, the intermediate connection to the frame being merely a clamp.

In a machine intended for both static and dynamic balancing, a further final control 21 is provided, preferably of the same type, with the strip set parallel to the strip 9 of the primary control. The strip 21 is shown connected to the base at 22 and 23 and to the frame at 24. When the machine is used for dynamic balancing this control is put out of action by releasing its intermediate clamp; when it is used for static balancing, the controls for the dynamic balancing are put out of action.

In machines intended for static balancing only, the initial axial control and the final static control alone are fitted and preferably are arranged as far apart as is otherwise convenient. Ade-

quate control in machines for static balancing only can sometimes be provided by making the supporting members of sufficient lateral rigidity in the A—A direction so that no other control is then necessary, every point of the frame being adequately constrained to move perpendicular to the line A—A with sufficient accuracy.

In a complete machine, the frame carries the rotor R by bearings in brackets arranged to adjust along ways formed on the frame so that its axis is co-linear with the axis of the apparatus 25 for determining the mass-radius-length correction necessary and its phase. Suitable means are provided for driving the rotor and the connected apparatus 25.

Obviously various changes in the form, construction, arrangement and combination of the several parts of my new apparatus may be made and substituted for those herein shown and described without departing from the nature and principle of my invention as set forth in the following claims.

I claim:

1. A machine for testing the balance of rotors and the like comprising a frame adapted to support the rotor to be tested with its axis disposed parallel to the plane of the frame, a stationary base, stiffly flexible supports extending from the base for supporting the frame for substantially planar movement parallel to the base, a plurality of taut flexible members extending a spaced distance from and substantially parallel to the plane of the frame, one of said flexible members disposed longitudinally and another of said flexible members disposed transversely of the frame, means for securing the ends of the flexible members to the base, and means for connecting the frame to either of the flexible members at an intermediate point thereof to restrain planar movement of the frame in a direction parallel to the flexible member to which it is connected.

2. A machine for testing the balance of rotors and the like comprising a frame adapted to support the rotor to be tested with its axis disposed parallel to the plane of the frame, a stationary base, means for supporting the frame for substantially planar movement parallel to the base, a plurality of taut flexible members extending a spaced distance from and substantially parallel to the plane of the frame, one of said flexible members disposed longitudinally and another of said flexible members disposed transversely of the frame, means for securing the ends of the flexible members to the base, and means for connecting the frame to either of the flexible members at an intermediate point thereof to restrain planar movement of the frame in a direction parallel to the flexible member to which it is connected.

JAMES JOHN GUEST.
